US00D664684S

(12) **United States Design Patent**
Carroll et al.

(10) **Patent No.:** US D664,684 S
(45) **Date of Patent:** ** Jul. 31, 2012

(54) **LED-BASED LIGHT BULB**

(75) Inventors: **David W. Carroll**, Grantsburg, WI (US);
Terry Travis, Nerstrand, MN (US);
Wendell Carroll, Minneapolis, MN (US)

(73) Assignee: **Forever Bulb, LLC**, Grantsburg, WI (US)

(**) Term: **14 Years**

(21) Appl. No.: **29/400,921**

(22) Filed: **Sep. 2, 2011**

(51) LOC (9) Cl. **26-04**

(52) U.S. Cl. **D26/2**

(58) **Field of Classification Search** D26/1-4;
313/313, 315, 316, 317, 318, 493; 315/52,
315/53, 56, 57, 58

See application file for complete search history.

(57) **CLAIM**

The ornamental design for a LED-based light bulb, as shown and described herein.

DESCRIPTION

FIG. 1 is a perspective view of an LED-based light bulb in accordance with the present disclosure;
FIG. 2 is a top plan view of the light bulb of FIG. 1;
FIG. 3 is a bottom plan view of the light bulb of FIG. 1;
FIG. 4 is a front plan view of the light bulb of FIG. 1;
FIG. 5 is a rear plan view of the light bulb of FIG. 1;
FIG. 6 is a side view of the light bulb of FIG. 1;
FIG. 7 is an opposite side view of the light bulb of FIG. 1;
FIG. 8 is a perspective view of another LED-based light bulb in accordance with the present disclosure;
FIG. 9 is a top plan view of the light bulb of FIG. 8;
FIG. 10 is a bottom plan view of the light bulb of FIG. 8;
FIG. 11 is a front plan view of the light bulb of FIG. 8;
FIG. 12 is a rear plan view of the light bulb of FIG. 8;
FIG. 13 is a side view of the light bulb of FIG. 8; and,
FIG. 14 is an opposite side view of the light bulb of FIG. 8.
